The ornamental design for a compact light valve projector, as shown.

DESCRIPTION

FIG. 1 is a front perspective view of a compact light valve projector embodying our design;

FIG. 2 is a rear elevation thereof;

FIG. 3 is a front elevation thereof;

FIG. 4 is a top view thereof;

FIG. 5 is a bottom view thereof;

FIG. 6 is a right side elevation thereof; and,

FIG. 7 is a left side elevation thereof.
